(57) **CLAIM**

We claim the ornamental design for an x-ray apparatus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an x-ray apparatus according to a first embodiment.

FIG. 2 is a rear view of the x-ray apparatus according to the first embodiment.

FIG. 3 is a top view of the x-ray apparatus according to the first embodiment.

FIG. 4 is bottom view of the x-ray apparatus according to the first embodiment.

FIG. 5 is a view from the right side of the x-ray apparatus according to the first embodiment.

FIG. 6 is a view from the left side of the x-ray apparatus according to the first embodiment.

FIG. 7 is a perspective view of the x-ray apparatus according to the first embodiment.

FIG. 8 is a front view of an x-ray apparatus according to a second embodiment.

FIG. 9 is a rear view of the x-ray apparatus according to the second embodiment.

FIG. 10 is a top view of the x-ray apparatus according to the second embodiment.

FIG. 11 is bottom view of the x-ray apparatus according to the second embodiment.

FIG. 12 is a view from the right side of the x-ray apparatus according to the second embodiment.

FIG. 13 is a view from the left side of the x-ray apparatus according to the second embodiment; and,

FIG. 14 is a perspective view of the x-ray apparatus according to the second embodiment.

The portions of the x-ray apparatus shown in broken lines form no part of the claimed design.
